UNITED STATES PATENT OFFICE.

JOHN R. KLIN, OF DAYTON, OHIO, ASSIGNOR TO THE GERMLESS PAPER CUP COMPANY,
OF DAYTON, OHIO, A CORPORATION OF OHIO.

HOLDER FOR PAPER CUPS.

1,239,277.

Specification of Letters Patent. Patented Sept. 4, 1917.

Application filed November 20, 1916. Serial No. 132,367.

To all whom it may concern:

Be it known that I, JOHN R. KLIN, a citizen of the United States, residing at Dayton, in the county of Montgomery and State of Ohio, have invented certain new and useful Improvements in Holders for Paper Cups, of which the following is a specification.

This invention relates to holders for paper cups of the sanitary kind now in general use at soda fountains and other soft drink dispensaries.

The object of the invention is to provide a holder in which the paper cup may be readily inserted without the necessity of touching the cup with the hands and also one which will be simple in construction, economical in manufacture and effective in use.

In the accompanying drawings:—

20 Figure 1 is a vertical section of the holder and cup.

Fig. 2 is a top plan view of the holder.

Fig. 3 is a perspective view of the apex end of the paper cup which the holder is 25 designed to receive.

Fig. 4 is a bottom plan view of the holder.

Referring to the drawings, 1 represents a base having an upwardly extending neck 2, the upper exterior portion of which is reduced slightly to receive a thimble portion 3 integrally formed with the upwardly extending and outwardly flaring main portion 4 of the holder. This portion 4 is in the nature of an inverted frustum of a cone, the cut-off apex portion of which has been replaced by the integrally formed thimble 3.

The neck 2 is formed with a screwthreaded interior 5, the lower portion of which is closed by a plug 6 threaded therein and 40 the upper portion of which is flared outwardly as indicated at 7 so as to conform in inclination with the walls of the part 4.

In operation, the paper cups 8 which are of a shape to conform to the interior of the 45 portion 4 of the holder, are placed in stacks in a suitable container in the manner illustrated in my application Ser. No. 132,368, filed November 20, 1916, with the apexes of the cups extending upwardly. When it is 50 desired to insert a cup into the holder, the holder is inverted and placed over the stack of cups, pressed firmly downward and given

a few turns so as to cause the screwthreads to engage the apex of the outermost cup, after which the holder may be withdrawn 55 with that cup firmly secured therein. In order to insure the proper engagement of the apex end of the cup with the screwthreads, the extreme point or apex of the cup is provided with a filler 9 of material 60 such as paraffin, which braces the walls of the cup at the apex end thereof and allows the screwthreads to impinge the same in a manner to firmly secure the apex of the cup within the screwthreaded neck. After use 65 the cup may be readily disengaged from the holder by giving the same a few turns and pulling the same bodily therefrom.

This holder is one especially intended for the long narrow cone-shaped cups which are 70 intended especially for soda water and drinks of that character.

When it is desired to clean the interior of the holder, the plug 6 may be removed so that access may be had to the extreme lower 75 end of the cup portion 4, as well as the screwthreaded interior of the neck 2.

Having thus described my invention, I claim:—

1. In a holder for paper cups, a main portion of flaring form, and non-elastic engaging surfaces at the extreme lower end thereof arranged to engage the extreme apex end of a conical paper cup by a twisting action of said main portion. 80

2. In a holder for paper cups, a main portion of flaring form, a base, a neck connecting said base and main portion, said neck being provided with non-elastic engaging surfaces arranged to engage the extreme 90 lower end of a conical paper cup by a twisting action of said holder.

3. In a holder for paper cups, a main portion of flaring form, and screwthreads at the extreme lower end thereof to engage the 95 apex end of a conical paper cup by a twisting action of said main portion.

4. In a holder for paper cups, a main portion of flaring form, a base, and a neck connecting said base and main portion, said 100 neck being provided with a screwthreaded interior for the purpose of engaging the apex end of a conical paper cup by a twisting action of the holder.

5. In a holder for paper cups, a base, a main portion of flaring form extending up from said base to form a support for a conical paper cup, and screwthreads formed 5 at the juncture of said base and flaring portion to engage the apex end of said conical paper cup.

In testimony whereof I have hereunto set my hand this 14th day of November, 1916.

JOHN R. KLIN.
